PICK.

1,010,755.

Specification of Letters Patent. Patented Dec. 5, 1911.

Application filed September 30, 1910. Serial No. 584,679.

To all whom it may concern:

Be it known that I, FRANK S. HARRINGTON, a citizen of the United States, residing in the city of Bridgeport, county of Fairfield, and State of Connecticut, have invented certain new and useful Improvements in Picks; and I do declare the following to be a full, clear, and exact description of the invention, such as will enable others skilled in the art to which it appertains to make and use the same.

My invention relates to certain new and useful improvements in picks, but more particularly has reference to the manufacture 15 of a device of this description in sections so that when a part becomes broken or worn a new part may be substituted therefor without the necessity of discarding the pick altogether for a new one.

With these ends in view my invention 20 consists in certain details of construction hereinafter fully described and then particularly pointed out in the claim which concludes this description.

In the accompanying drawing Figure 1 is 25 an elevation of my improved pick—Fig. 2 an elevation showing the parts of my improvement assembled with one of the eye sections removed—Fig. 3 a section at the line x, x , of Fig. 1—Fig. 4 a detail enlarged 30 view of the interior of one of the eye sections, and Fig. 5 a view similar to Fig. 2 but showing the parts of my improvement assembled in a slightly different manner 35 such as would be suitable in the instance of a straight pick.

Similar numerals of reference denote like parts in the several figures of the drawing.

1 are the eye sections which have formed 40 integral therewith curved portions 2 that are complementary of the eye, and interior of each of these sections and on opposite sides of the portions 2 are wedge shaped oppositely disposed recesses 3 which are perforated at 4 for the purpose presently to be explained.

5 are the pick points of any suitable and approved shape, the heel ends of which are wedge shaped and provided with elongated 45 slots 6.

In the usual form of pick, such as is commonly used, the pick points slope toward the inner end of the handle 7 as shown at Figs. 1 and 2, and in the present instance this is

brought about by merely assembling the 55 eye sections 1 and points 5 as is shown particularly at Fig. 2, wherein the inclined walls of the recesses 3 are nearest the inner end of the handle 7, but in case a straight pick is desired, such as is commonly used 60 in coal mines, the parts would be assembled as is shown at Fig. 5, wherein the inclined walls of the recesses 3 are nearest the outer end of the pick.

In assembling the parts of my improvement, the wedge shaped heel ends of the pick points are forced within the recesses 3, and the sections 1 are clamped firmly 65 against these heel ends by means of bolts 8 passed through the perforations 4 and slots 70 6, these bolts having threaded outer ends which preferably engage with the threaded walls of the perforations 4 in one of the sections 1, nuts 9 being threaded on the extremities of these bolts for the purpose of 75 clamping the sections 1 against said heel ends, the thickness of the latter being slightly greater than the combined depth 80 of the recesses which contain them, so that the sections 1 may be firmly clamped against said ends.

The handle 7 is driven within the eye formed by the curved portions 2 in the usual manner.

In Fig. 5, the handle eye is tapered 85 oppositely from that shown in the other form of the invention, necessitating the use of a handle of special form.

Constant use of the pick will cause the heel ends to be driven more firmly within 90 the recesses 3, and this will be accomplished without the slightest shock against the bolts 8 owing to the fact that the latter extend freely through the elongated slots 6 in these heel ends, and this is a very important feature 95 since if the shock occasioned by the use of the pick is sustained either by the bolts or by any part having contact with the latter, these bolts are very apt to become bent or broken and the pick itself thereby rendered useless.

In my improvement, the pick points, in the event of breakage or undue wear, are readily replaced by new points, and the same is true of the eye sections.

105 Various kinds of points may be utilized in connection with my improvement so that the latter may be employed as a mattock,

a millstone hammer, a mill pick, &c., and my invention is therefore not limited in this respect so long as the points are provided with the wedge shaped heel ends.

5 Having thus described my invention what I claim as new and desire to secure by Letters Patent is:—

10 A pick head composed of a pair of similar sections, each having a central transverse curved portion conjointly forming a handle receiving eye, and each further having a wedge-shaped recess on each side of the curved portion thereof communicating with the latter, and extending through the end of said sections, pick points having wedge-shaped heels received in said recesses, and formed with longitudinal slots, bolts passed

through the sections and extending through said slots, said slots being of considerably greater length than the diameter of the bolt, 20 and being arranged so that the bolts extend adjacent the inner end of the slot, to thereby permit the pick points to have an inward movement with respect to the bolts, the inner ends of said wedge-shaped recesses being each closed by the handle, the handle extending in the eye formed by said sections. 25

In testimony whereof I affix my signature in presence of two witnesses.

FRANK S. HARRINGTON.
